(57) **CLAIM**

The ornamental design for a double tier cat tent, as shown and described.

DESCRIPTION

FIG. 1 is a front perspective view of a double tier cat tent showing my new design.

FIG. 2 is rear perspective thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with "9" in FIG. 2.

The short evenly dashed broken lines shown in the figures illustrate portions of the double tier cat tent that form no part of the claimed design. The long-dash short-dash long-dash broken lines in FIGS. 2 and 9 show the boundaries for the enlarged view shown in FIG. 9, and form no part of the claimed design.
